UNITED STATES PATENT OFFICE.

ROBERT WILSON, OF ST. LOUIS, MISSOURI.

ADVERTISING APPARATUS.

SPECIFICATION forming part of Letters Patent No. 787,420, dated April 18, 1905.

Application filed December 12, 1904. Serial No. 236,624.

To all whom it may concern:

Be it known that I, ROBERT WILSON, a citizen of the United States, residing at St. Louis, Missouri, have invented a new and useful Advertising Apparatus, of which the following is a specification.

This invention relates to advertising apparatus, and comprises the novel combination, arrangement, and association of parts, as hereinafter shown, described, and claimed.

The object of this invention is to provide an advertising apparatus comprising one or more displays, such as cards or objects, arranged upon movable supports connected by gear or pulley-and-belt mechanism with a motor device for moving the cards or objects, thereby more surely to attract attention of the public. The entire mechanism is preferably supported upon a pivot, so that the displays may be turned toward either direction and to accommodate the motor.

In the drawings, Figure 1 is a front elevation of the device in which the motor employed is a windmill. Fig. 2 is a plan view of the same.

The apparatus is designed especially for operation by wind and is arranged in connection with an image of some animal by means of crank-and-limb connection in order to give the appearance of being propelled by such image. With such purposes in view I provide a base 1, upon which is pivoted a supporting member 2, the latter carrying two vertical posts 3. The upper ends of the posts 3 carry a shaft 4, upon which is mounted a wind-wheel 5, the blades of which may be of either wood or metal or other material found to be suitable. A vane 6 is attached to one end of the shaft 4, so that the displays will be held to windward. A small pulley or wheel 7 is attached to the hub of the wind-wheel 5. Two arms 8 project horizontally and parallel from the posts 3 and support a rod or shaft 9, upon which is a large pulley or wheel 10. A belt or chain 11 passes around the two pulleys or wheels 7 and 10, so that when the wind-wheel is driven the said wheel 10 and the rod or shaft 9 will be rotated. The shaft 4 carries a sleeve 12 separate from the hub of the wind-wheel 5, and a pulley or wheel 13 is

fixed thereon. A small pulley or wheel 14 is attached on the rod or shaft 9, and a belt or chain 15 passes around said two pulleys or wheels 13 and 14, so that when the wind-wheel 5 is rotated the sleeve 12 will also be rotated, but owing to the differential belt-and-pulley connection the said sleeve will be driven at a much slower speed than the wind-wheel. A series of arms 16 are attached to a hub 17 on the sleeve 12 and project radially. The outer end of each of said arms 16 is bent, as indicated at 18, to provide means of attachment for the objects or displays, such as 19. The displays are pivotally connected to the arms 16, and therefore maintain a relatively constant position. These displays may be in the form of cards containing printed matter, or objects themselves, or forms signifying any particular class of goods or merchandise, or cut to represent trade-marks, or, in fact, any preferred type of displays.

To increase attraction and enhance novelty of appearance, a form of some animal, such as 20, is connected, by means of a flexible limb, to a crank 21 on one end of the rod or shaft 9, so that when the device is in operation the crank will oscillate the flexible limb, giving the appearance that the animal-form supplies the motive power. The animal image 20 may typify any class of articles, as well as the displays on the arms 16. The image 20 is mounted upon a platform 22, connected to one of the posts 3.

I claim—

1. An apparatus of the class described, comprising a shaft, a motor-wheel on said shaft, a series of revoluble arms upheld by said shaft, differential driving connections operable by the motor-wheel and adapted to move the arms at slower speed than the motor-wheel, an animal-form having a flexible limb connected to part of the driving connections, for the purpose specified, and a pivotally-supported frame supporting all of said parts.

2. An apparatus of the class described comprising a motor-wheel, a shaft supporting said wheel, a sleeve upon said shaft, arms attached to said sleeve, and adapted to carry displays, differential driving connections between the motor-wheel and said sleeve, to

move the latter at slower speed than the wheel, and an image having a flexible limb connected to part of the driving connection, for the purpose specified.

3. An apparatus of the class described comprising, a base, a frame pivoted thereon, a shaft carried by said frame, a motor-wheel on said shaft, a sleeve on said shaft, displays carried by said sleeve, a shaft 9, connections for rotating the shaft 9 when the motor-wheel moves, connections from the shaft 9 to the said sleeve and an image having a flexible limb leading to the said shaft 9.

4. An apparatus of the class described, comprising a frame, a shaft 4 carried by said frame, a motor-wheel on said shaft, a wheel 7 connected to the hub of said motor-wheel,

a shaft 9, a wheel 10 thereon, a belt 11 passing around said wheels 7 and 10, a second wheel 14 on said shaft 9, a sleeve separate ²⁰ from the motor-wheel on said shaft 4, a wheel 13 on said sleeve, a belt passing around said wheels 14 and 13, a series of arms adapted to carry displays attached to said sleeve, a crank on the shaft 9, and an image having a flexible ²⁵ limb connected to the said crank, substantially as specified.

In testimony whereof I have signed my name to this specification in the presence of two subscribing witnesses.

ROBERT WILSON.
